UNITED STATES PATENT OFFICE.

ETHEL R. WILCOX, OF CONCORDIA, KANSAS.

TABLE OR LEAF FOR HIGH CHAIRS.

1,178,894.

Specification of Letters Patent. Patented Apr. 11, 1916.

Application filed April 20, 1915. Serial No. 22,565.

To all whom it may concern:

Be it known that I, ETHEL R. WILCOX, a citizen of the United States, residing at Concordia, in the county of Cloud and State of Kansas, have invented a new and useful Table or Leaf for High Chairs; and I do hereby declare the following to be a full, clear, and exact description of the invention, such as will enable others skilled in the art 10 to which it appertains to make and use the same.

This invention relates to an improved table or leaf for high chairs, and an object of the invention is to provide a simple, efficient and practical device of this nature having improved means for attaching the leaf or table to the high chair, so it can be readily detached, by simply raising the outer portion upwardly, and then slidably 20 disconnecting the same.

A further object is to construct a table or leaf for a high chair of aluminum, thereby rendering the same light in weight and durable in use, and which may be easily 25 washed after being used.

A further object of the invention is to provide a table or leaf constructed of aluminum having a peripheral flange, adjacent which a gully or groove is constructed, into 30 which the waste or spilt food may flow, owing to the bottom of the table or leaf being convexed upwardly, and which bottom is provided with crossing grooves or gullies to drain the spilt food to the gully adjacent 35 the flange, there being an aperture adjacent the gully of the flange, through which the waste food may flow into a suitable receptacle, and this aperture may be closed by 40 any suitable means, such as a cork or the like.

In practical fields the details of construction may necessitate alterations, falling within the scope of what is claimed.

The invention comprises further features 45 and combination of parts, as hereinafter set forth, shown in the drawings and claimed.

In the drawings:—Figure 1 is a view in perspective of a high chair showing the improved table or leaf applied thereto. Fig. 50 2 is an enlarged detail perspective view of the improved leaf or table, showing the semi-circular lugs, and a correspondingly shaped socket to receive one of the lugs. Fig. 3 is a sectional view on line 3—3 of 55 Fig. 1. Fig. 4 is a sectional view on line

4—4 of Fig. 2. Fig. 5 is a detail view showing the inclination of the walls 6^b.

Referring more especially to the drawings, 1 designates a high chair which may be of any conventional construction and provided 60 with the arm rests 2, each of which is cut away at 3 forming a recess, in which a plate 4 is secured and shown at 5. These plates are provided with substantially semi-circular sockets 6, to receive the correspondingly 65 shaped lugs 7 formed integrally upon the end portions of the leaf or table 8. This leaf or table including the lugs is stamped or pressed into the shape and construction shown from a single piece of sheet aluminum. The bottom 9 of the leaf or table is convexed slightly upwardly, from the outer portions toward the center, as shown clearly 70 in Figs. 3 and 4, and is provided with crossing gullies or grooves 10. When the table 75 or leaf is constructed or pressed into shape, the same is formed with a flange 11, which extends upwardly, is curved at 12, and then extends downwardly forming the downwardly yieldable flange 13, on which, at the 80 ends of the leaf or table, the semi-circular lugs 7 are formed. Adjacent the flange 11, the leaf or table is constructed with a groove or gulley 14, into which the crossing grooves 85 10 merge, so as to drain the waste or spilt food into the groove 14, from which it may be drained, through the flanged aperture 15, by removing the cork or similar stopper 16.

Each socket 6 has an abutment wall 6^a, which is engaged by the end portion 7^a of the lug 7, and the wall 6^b of each socket inclines downwardly and rearwardly and toward the corresponding wall of the opposite socket, so that in arranging the leaf or table in place, the lugs wedge into place. 95

The invention having been set forth, what is claimed as new and useful is:—

1. A leaf for a high chair constructed or stamped upon the sheet metal comprising a bottom, an endless flange rising upwardly 100 from the bottom adjacent its outer portion, said flange being curved over and downwardly forming a downwardly extending yieldable flange, sockets on the arm rests of the chair, and lugs upon said downwardly 105 extending flange at both ends of the leaf to engage said sockets, the downwardly extending flange being designed to yield as the lug enters the socket.

2. A high chair table leaf connection, com- 110

prising, in combination, a downwardly extending yieldable flange extending about the leaf, socket plates oppositely disposed and secured upon the arm rests of the chair, said socket plates having corresponding sockets curved from the top of the plate, which top is flush with the top of the arm rest, downwardly and toward the back of the chair and terminating in abutment walls, the inner wall 10 of each socket being inclined downwardly, rearwardly and toward the corresponding wall of the opposite socket, and lugs formed on the downwardly extending yieldable flange

upon both ends of the leaf and being oppositely disposed and being curved correspondingly to the socket and designed to wedge between the downwardly and rearwardly inclined walls of the sockets, the flange of the leaf yielding as the lugs enter the sockets.

In testimony whereof I have signed my 20 name to this specification in the presence of two subscribing witnesses.

ETHEL R. WILCOX.
